UNITED STATES PATENT OFFICE

LARKIN ALONZO HACKER, OF VERNON, TEXAS

STALK CUTTER

Application filed September 4, 1929, Serial No. 390,294. Renewed January 21, 1933.

The present invention relates to a stalk cutter and the objects of the invention will become apparent from a detailed consideration of the following description taken in conjunction with the accompanying drawings, wherein:

Figure 1 is a top plan view of the stalk cutter embodying the features of my invention.

10 Figure 2 is a rear elevation thereof.

Figure 3 is a vertical longitudinal section therethrough taken substantially on the line 3—3 of Figure 2.

15 Figure 4 is a detail section taken substantially on the line 4—4 of Figure 2.

Figure 5 is a vertical longitudinal section showing the marker attachment in place of the cutters.

20 Figure 6 is a top plan view of the marker attachment.

Figure 7 is a detail section through the axle showing an attachment wheel.

25 Figure 8 is an elevation taken at right angles to the view shown in Figure 7.

Figure 9 is an enlarged detail section showing the manner of mounting the marker attachment, and,

30 Figure 10 is a sectional view taken substantially on the line 10—10 of Figure 9.

Referring to the drawings in detail, it will be seen that the numeral 5 denotes an elongated axle having wheels 6 journalled on the ends thereof. Tubular risers 7 extend upwardly from intermediate portions of the axle 5, thereof one to each side of the center thereof and said risers telescopically receive therein tubular members 8 connected by a cross member 9.

35 Springs 10 are disposed in the tubular risers 7 and the tubular members 8 and provide a resilient mounting for the frame of the machine. Plates 11 extend forwardly from the cross member 9 and receive therebetween a tongue structure 12 on which is mounted a seat 14. Braces 15 connect the plates 11 and the tubular members 8. A lever 16 is pivotally mounted intermediate its ends on the tongue and has a detent

structure 17 cooperating with the notched segment 18 on the tongue.

Bearings 19 have sleeves 20 adjustably mounted on the risers 7 by means of set screws 21. A rocker shaft 22 is mounted in the bearings 19 to extend transversely across the frame rearwardly of and above the axle 5. A plurality of shields 23 are mounted on this rocker shaft. Arms 24 are fixed to the ends of the rocker shaft and are downwardly and rearwardly inturned and are slightly curved upwardly as indicated in Figure 3.

Arms 25 have bearings 26 rockable on the end portions of the axle 5 and said arms terminate in sleeves 27 in which is fixed a shaft 28. Yokes 29 rise from the sleeves 27 and have rollers 30 journalled thereon to rest on the arms 24. An arm 31 is fixed to an intermediate portion of the rocker shaft 22 and a link 33 is engaged therewith and adjustably engaged with the lower end of the lever 16 as indicated at 34. A plurality of cutter drums 35 are rotatable on the shaft 28 and have blades 36 radiating outwardly therefrom.

Obviously by rocking the lever 16, the drums 35 may be let down in engagement with the ground or raised free therefrom. In place of the drums 35, it will be seen that arms 38 having sleeves 39 may be fixedly mounted on the shaft 28 by means of set screws 40 in a manner to extend rearwardly therefrom. Arms 41 each having formed on one end a pair of spaced bearings 42 which are rockable on a shaft 43. This shaft 43 is fixedly mounted in the sleeves 44 on the rear ends of the arms 38. Discs 45 for marking purposes are journalled on the rear or free ends of the arms 41.

40 A collar 47 is fixed on the shaft 43 between each pair of bearings 42 by means of a set screw 50 and has a bracket 51 extending therefrom over the adjacent arm 41 and a spring 53 impinges against the brackets 51 and the arms 41 to hold the respective discs 45 down into engagement with the ground.

45 A bridgepiece 54 extending between each pair of the bearings 42 is adapted to abut the set screws 50 to limit the downward swing-

ing movement of the arms 41. Obviously, therefore, the marker discs 45 may be raised or lowered by manipulating the lever 16.

One of the wheels 6 may be removed and 5 in place thereof a yoke 60 may be journaled on the axle 5 with a wheel 61 journaled between the extremities thereof. A curved crank arm 62 extends from the yoke 60 and has rack teeth 63 engageable with a gear segment 64 on the rocker shaft 22 so that when 10 this rocker shaft is rocked by the lever 16, the yoke 60 will be swung to lower and raise the side of the frame as will be apparent.

This stalk cutter is of two or three or 15 more row construction. When the structure disclosed in Figures 7 and 8 is substituted for one of the wheels 6, the stalk cutter is adapted to listed row cutting.

It is thought that the construction, operation, utility and advantages of this invention will now be quite apparent to those skilled in this art without a more detailed description thereof. The present embodiment of the invention has been disclosed in 25 considerable detail merely for the purposes of exemplification, since in actual practice it attains the features of advantage enumerated as desirable in the statement of the invention and the above description.

30 It will be apparent that changes in the details of construction, and in the combination and arrangement of parts may be resorted to without departing from the spirit or scope

of the invention as hereinafter claimed or sacrificing any of its advantages.

Having thus described my invention, what I claim as new is:

1. A machine of the character described comprising an axle, supporting wheels journaled on the axle, risers mounted on the axle, bearings mounted on the risers, a rocker shaft journaled in the bearings, means for actuating the rocker shaft, rockable arms on the axle, a shaft fixed to the rockable arms, yokes fixed to the rockable arms, lifting arms fixed to the rocker shaft and operatively engaged with the yokes in a manner to raise and lower the second named shaft, and cutting members operatively mounted on said second named shaft. 70

80 2. A machine of the character described comprising an axle, supporting wheels journaled on the axle, risers mounted on the axle, bearings mounted on the risers, a rocker shaft journaled in the bearings, means for actuating the rocker shaft, rockable arms on the axle, a shaft fixed to the rockable arms, yokes fixed to the rockable arms, lifting arms fixed to the rocker shaft and extending into the yokes for raising and lowering the second named shaft, rollers journaled on the yokes and adapted to ride on the lifting arms, and cutting members operatively mounted on 90 said second named shaft. 95

In testimony whereof I affix my signature.

LARKIN ALONZO HACKER.
